UNITED STATES PATENT OFFICE.

HARRY DE WITT ELSE, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC HEATING DEVICE FOR LAUNDRY MACHINES.

Application filed July 31, 1924. Serial No. 729,230.

This invention relates to improvements in electric-heating elements for ironing machines and, more particularly, to thermostatically-controlled heating elements.

The object of the invention, generally stated, is the provision of an electric heating element that is simple and efficient in operation, readily and economically manufactured.

10 A more specific object of the invention is to provide for the automatic control of the supply of electrical energy to maintain the temperature between certain limits.

15 A further object of the invention is to effect a cutting off of the supply of electrical energy in a manner that avoids damage to the apparatus through arcing.

20 It is also an object of the invention to provide for the variation of the limits of temperature at which the apparatus will function.

Other objects of the invention will, in part, be obvious and in part appear herein-after.

25 This invention, accordingly, is disclosed in the embodiment thereof shown in the accompanying drawing and comprises the features of construction, combination of elements and arrangement of parts which will 30 be exemplified in the construction herein-after set forth and the scope of the application of which will be indicated in the claims.

For a fuller understanding of the objects 35 of the invention, reference should be had to the following detailed description, taken in connection with the accompanying drawing, in which

Figure 1 is a perspective view of an ironing machine, parts being broken away to 40 show a heating element in accordance with this invention;

Fig. 2 is a diagram of the connections showing the circuit controlled by the thermostat closed; and

45 Fig. 3 is a diagram of the connections showing the circuit controlled by the thermostat open.

Referring now to the drawing, 10 designates, generally, an ironing machine of a well-known type, provided with a roll 11 and a movable ironing shoe 12. Since the ironing shoe may be moved toward and

away from the roll, it is the usual practice to provide the heat necessary for the ironing operations by heating the shoe. Accordingly, as shown in Fig. 1, an electric element 14, to be described hereinafter, is mounted in the shoe. However, in order to meet the requirements of different constructions, the electric heating element may be mounted in either ironing member or disposed in any desirable manner to effect the heating of one or both of the ironing members.

It will be readily understood that an electric heating element does not require a particular design of ironing member, but may be constructed to conform to the shape and size of the ironing member. The heating element 14 may be mounted in any ironing member in any suitable manner, such, for example, as by fixing it in spaced relation to the ironing member by means of insulators and insulated screws.

The heating element shown, generally, at 14, includes a plurality of separate resistance members 15, 16 and 17. As shown in Figs. 2 and 3, the resistance members 15 to 17, inclusive, are connected in parallel across the source of supply of electric energy, which, in this case, is the line wires 18. However, it will be readily understood that they may be connected in other ways and still give the desired heating effect.

Referring now to Figs. 2 and 3, it will be seen that the resistance member 15 is connected across the source of supply 18 and the supply of electric energy to the resistance member is controlled by means of a manually-operated switch 13 interposed between it and the line. The resistance members 16 and 17 are connected in parallel and across the same source of supply of electric energy as the resistance member 15. In order to control the supply of electric energy to the resistance members 16 and 17, a switch 19 is located in the circuit between the line and common terminal, shown at 20. The switch is of the relay type and is operated by means of an electromagnet 21.

In order to provide for the operation of the switch 19, an electric circuit is provided whereby the electromagnet 21 may be energized from the resistance member 15 of the heating element. With a view to avoiding

damage from arcing, the winding of the magnet 21 is constructed from low-resistance wire so that sufficient current for its energization may flow therethrough upon applying a small voltage which may be supplied by connecting it across a relatively small portion of the resistance member 15.

Since it is desired to obtain automatic operation of the switch 19 to control the heating of the shoe 12, a thermostat, operable upon changes in temperature of the heating shoe, is provided for making and breaking the circuit of the electromagnet 21. The thermostat includes the ironing shoe 12 which, in this embodiment, carries suspended from its lower portion, a rod 28 of invar or some other suitable material not subject to changes in length by variations of temperature within the range required for carrying out ironing operations. As will be observed, in this particular construction, the rod 28 is suspended by means of two hangers 27, attached to the lower portion of the shoe.

In order to provide for the adjustment of the rod, it is slidably disposed in one of the hangers while a threaded portion of the rod engages an internal thread provided in an opening formed in the other hanger, which is located near the end of the shoe, as shown in Fig. 1. A hand wheel 30 is fixed to the rod 28 so that the latter may be adjusted in the hangers. Attached to the rod 28 is a contact member 24 preferably made from some metal not subject to corrosion and the formation of the coating of insulating material by the action of steam and the atmosphere.

Disposed in alignment with the contact member 24 is a contact plate 23, the latter being fixed to a bar 26. Both members 23 and 26 are of some metal efficient as a conductor of electricity and lines of magnetic force. The bar 26, as shown in Figs. 2 and 3, is carried by a spring 29, attached to the frame of the ironing machine and it forms the core of an electromagnet, the function of which will appear in a subsequent paragraph.

Since it is desirable to establish a comparatively wide gap between the contact members 23 and 24 when the circuit is once broken, the core 26, carried by the spring 29 has mounted thereon a winding 22, connected in series with the winding of the electromagnet 21. The electromagnet, consisting of the winding 22 and the core 26, cooperates with the armature 25 carried by the rod 28 to establish a magnetic circuit to retain the contact members 23 and 24 in engagement as the rod 28 moves to the right until the spring has been energized sufficiently to overcome the magnetic attraction, when the spring will function to carry the contact plate 23 away from the contact mem-

ber 24. On examining Figs. 2 and 3, it will be seen that the circuit of the electromagnet 21 includes the winding 22, core 26, plate 23, contact member 24 and a portion of the resistance member 15, all connected in series. 70

It will be readily understood that, as the rod 28 is projected against the plate 23, the spring 29 will be flexed. Thus, the spring 29 has a second function, in that it serves to protect the parts of the apparatus from damage during operation if the rod 28 has not been set with great accuracy. 75

In mounting the switches 13 and 19, a switch box 32 may be provided and attached to the ironing machine frame, as shown in Fig. 1. In this particular construction, the switch 19 is located in the switch box 32 while the switch 13 is disposed on its front wall so that it may be manually operated without opening the box. The conductors leading from the source of supply 18 to the switches and the heating elements, may be enclosed in conduits, such as 33. 80

In operation, when it is desired to heat the ironing shoe 12, the rod 28 is set to place the contact members 23 and 24 in engagement and then the switch 13 is manually operated, connecting the resistance member 15 of the heating element across the source of electric energy 18. Since the circuit of the electromagnet 21 is closed, the winding of the electromagnet is connected across a portion of the resistance member 15. This results in the energization of the electromagnet 21 and the closing of the switch 19, connecting the resistance members 16 and 17 of the heating element in parallel across the source of electric energy. The heating element 14 is now operating at full capacity 100 and the shoe is quickly brought to the desired temperature. 105

As the temperature of the shoe gradually increases, it expands, drawing the rod 28, as shown in Figs. 2 and 3, to the right. During the first part of the movement of the rod 28 to the right, the energized solenoid 22, which has established a magnetic circuit through the armature 25, causes the spring 29 to follow, maintaining the contact members 23 and 24 in engagement. However, when the rod 28 has moved a predetermined distance, the spring 29 is sufficiently energized to hold the plate 23 against further movement and the members 23 and 24 are separated. Instantaneously with the breaking of the contact between members 23 and 24, the solenoid 22 is de-energized and the spring 29 acts to effect a movement of the contact plate 23 away from contact member 24. The spring 23 may vibrate, but the amplitude of vibration will continually decrease so that the contact members 23 and 24 are not brought into engagement. 110

In this particular construction, an electromagnet is shown for maintaining the con- 130

fact members 23 and 24 in engagement during the first portion of the movement of the rod 28. However, it will be readily understood that any permanent magnet might be substituted therefor. In fact, efficient operation may be effected without the use of a magnet.

In designing the resistance member 15, its heating capacity is limited so that it will not raise the temperature of the ironing shoe above the ironing temperature when the machine is not in operation. If now articles to be ironed are introduced into the ironing machine, the shoe 12 gives off its heat to the articles being ironed, it contracts and projects the rod 28, as viewed in Figs. 2 and 3, to the left, establishing contact between the contact members 23 and 24, again completing the circuit of the electromagnet 21. This results in the closing of the switch 19 and the connecting of the resistance members 16 and 17 of the heating element across the source of electric energy. The heating element 14 is again at full capacity and the shoe is maintained at an ironing temperature.

While the illustrated example constitutes a practical embodiment of my invention, I do not limit myself strictly to the exact details herein illustrated, since, manifestly, the same can be considerably varied without departing from the spirit of the invention, as defined in the appended claims.

I claim as my invention:

1. In an ironing machine, in combination, an ironing member which expands and contracts upon changes in temperature, a variable electrical heating element for the ironing member, and means disposed for actuation as the ironing member expands and contracts to control the heating element.

2. In an ironing machine, in combination, an ironing member subject to changes in size upon changes in temperature, an electrical heating element for the ironing member, means for controlling the heat delivered by the heating element, said control means being disposed for operation by the ironing member as it changes in size.

3. An automatic heat control for ironing machines comprising, in combination, an ironing member subject to changes in size upon changes in temperature, an electrical heating element for the ironing member, means for varying the heating capacity of the element, and means for actuating said heat-varying means disposed to be operated by the ironing member as it changes in size.

4. In an ironing machine, in combination, an ironing member, a plurality of resistance members adapted to be cut into and out of an electric circuit disposed to heat said ironing member, switching means operable to vary the number of resistance members

on changes in temperature of said ironing member to effect the operation of said switching means, said ironing member being the controlling member of the thermostat.

5. In an ironing machine, in combination, an ironing member, a plurality of resistance members adapted to be cut into and out of an electric circuit disposed to heat the ironing member, a switch adapted to vary the number of resistance members in the circuit and means operable upon the expansion and contraction of the ironing member to effect the operation of said switch.

6. In an ironing machine, in combination, an ironing member, a plurality of resistance members adapted to be cut into and out of an electric circuit disposed to heat the ironing member, said resistance members being connected in parallel, a switch adapted to vary the number of resistance members in the circuit, and means operable upon the expansion and contraction of the ironing member to effect the operation of the switch.

7. In an ironing machine, in combination, an ironing member, a plurality of resistance members adapted to be connected across a source of electric energy disposed to heat said ironing member, an electrically-operated switch adapted to vary the number of resistance members connected across said source of electric energy, and a thermostat adapted to control the operation of said switch, said ironing member being one of the members of the thermostat, thereby to control the operation of said switch by the expansion and contraction of the ironing member.

8. In an ironing machine, in combination, an ironing member, a plurality of resistance members adapted to be connected across a source of electric energy disposed to heat said ironing member, an electrically-operated switch adapted to vary the number of resistance members connected across said source of electric energy, and a thermostat operable to make and break said switch circuit to control the operation of said switch, said ironing member being one of the members of the thermostat, thereby to control the operation of the switch by the expansion and contraction of the ironing member.

9. In an ironing machine, in combination, an ironing member, a plurality of resistance members adapted to be connected across a source of electric energy disposed to heat said ironing members, and an electrically-operated switch adapted to vary the number of resistance members connected across said source of electric energy, and a thermostat adapted to make and break said switch circuit, said ironing member being one of the members of the thermostat, thereby to control the operation of the switch by the expansion and contraction of the ironing mem-

ber, the other member of the thermostat being disposed for movement toward and away from the ironing member.

10. In an ironing machine, in combination, an ironing member, a plurality of resistance members adapted to be connected across a source of electric energy disposed to heat said ironing member, an electrically-operated switch adapted to vary the number 10 of resistance members connected across said source of electrical energy, and a thermostat cooperative to control the operation of said switch, said thermostat comprising a contact member carried by the ironing member and connected in the switch circuit, and a second contact member adapted to move away from said first contact member on the breaking of the switch circuit.
11. In an ironing machine, in combination, 20 co-operative ironing members, a plurality of electric resistance members adapted to be connected to a source of supply of electric energy disposed to heat an ironing member, a manually operated switch adapted to connect a resistance member across said source of supply, an electrically operated switch adapted to connect the other resistance members across a source of supply, said electrically-operated switch being connected 30 across a portion of the resistance member controlled by the manually operated switch and means automatically operable to make and break said switch circuit.
12. In an ironing machine, in combination, 35 an ironing member, a heating element disposed to heat the ironing member, an electric-

cally operated switch adapted to vary the capacity of the heating element, an electric circuit to control the operation of said switch, and a thermostat operable to make 40 and break said circuit, said thermostat including the ironing member, a contact member carried by the ironing member and disposed to move upon the expansion and contraction of the latter, a second contact member disposed to receive said first-mentioned contact member, said second contact member being disposed for movement.

13. In an ironing machine, in combination, an ironing member, a heating element disposed to heat the ironing member, an electrically operated switch adapted to vary the capacity of the heating element, an electric circuit to control the operation of said switch, and a thermostat operable to make 50 and break said circuit, said thermostat including the ironing member, a contact member carried by the ironing member and disposed to move upon the expansion and contraction of the latter, a second contact member disposed to receive said first-mentioned contact member, said second contact member being disposed for movement; a magnet carried by one of said contact members, and an armature by the other contact member, 60 thereby to effect a movement of the contact members together.

In testimony whereof, I have hereunto subscribed my name this eighth day of July 1924.

HARRY D. ELSE.
